VERY HIGH GAIN TRAVELING-WAVE TUBE

Lothar Brück, Paris, France, assignor to Compagnie Générale de Télégraphie Sans Fil, a corporation of France

Application July 29, 1949, Serial No. 107,401
In France September 17, 1948

6 Claims. (Cl. 315—3)

1

My invention relates to a traveling-wave tube; its object is to provide a tube which has a very high gain and in which the possibility of self-oscillation is considerably reduced by a perfect decoupling inside the tube between the input and the output, in particular by dividing the total gain into several stages.

The advantage of a single tube that has a very high gain will be understood by considering that, for a transmission line which is composed of a plurality of relays and is provided with travelling-wave tubes, a gain of 60 or 80 db and a power of 0.5 or 1 watt are required per station. This desired gain is obtained by connecting in cascade several stages provided with travelling-wave tubes, each of which has a gain of 20 or 30 db, the output of the first tube being connected by means of a guide to the input of the second tube, and so forth. The transfer of the power from the tube to the guide, and conversely, is obtained by means of coupling elements, the degree of coupling of which varies with the frequency. As a result of this, the gain also varies with the frequency; consequently, the band-pass of any station, which is determined by the drop in the gain of 3 db below the maximum value, will be narrower as there are more stages in cascade, i. e. as there are more coupling elements through which the radio-frequency energy has to pass.

It is therefore desirable to obtain as high a gain as possible from a travelling-wave tube, so as to obtain the total gain required with a very small number of stages. For this purpose, for example, it is possible to increase the current that flows through the helix in the tube. But this produces a less efficient bunching of the electrons owing to the increase in the space charge which reduces the expected increase in the gain. Furthermore, in tubes which are constructed for a high gain, there exists the possibility of a portion of the radio-frequency energy being reflected by the output or by a discontinuity of the helix. If such energy reaches the input with a power which is equal to or greater than that of the input signal, it sets up self-oscillation. In order to prevent this, use is made of helices which are highly attenuated for radio-frequency energy, or of helices provided with a localized attenuation of 50 or 60 db so as to decouple the input and the output of the helix.

Helices with an attenuation distributed along their entire length have a disadvantage, viz. that such attenuation decreases the gain for a given current. On the other hand, a helix provided with a localized attenuation does not sufficiently

2

prevent the possibility of oscillation of the tube, since the output energy is not transmitted to the guide without reflection, whatever the frequency may be. Owing to this fact, and also because of the irregularities of the helix, reflections occur so that oscillations may be set up if the gain is high.

My invention enables a travelling-wave tube to be constructed, the gain of which is higher than it is possible to obtain with the tubes according to the heretofore known construction. Figs. 1 and 2 show in axial section two embodiments of the principles that enable this result to be obtained.

15 The invention will be explained with reference to Fig. 1. As in the tubes of usual construction, the cathode K_1 emits a beam of electrons which is directed parallel to the axis of the helix H_1 . The radio-frequency signal is introduced into the helix in the known manner by means of members not shown. The helix is manufactured of a material that has a low radio-frequency attenuation, so that the losses of radio-frequency energy in the helix are small. In order only to have waves which are propagated in the direction of the electrons along the helix, the end of said helix on the output side is in contact with a layer R_1 of resistance material arranged on the quartz rods T_1 or on the wire of the helix, said layer being matched at its input with the characteristic impedance of the helix, thereby preventing a reflection of the radio-frequency energy. After the electrons have passed through the helix H_1 , they are collected by the collector C_1 . The device comprising the cathode K_1 , the helix H_1 and the collector C_1 therefore differs from the known travelling-wave tubes only by the fact that the output end of the helix is matched for all frequencies and does not produce any reflection of the 20 radio-frequency energy. This already considerably lessens the probability of self-oscillation. Furthermore, in order to reduce the possibility of a self-oscillation of the tube caused by irregularities on the helix, the helix H_1 may be provided 25 with a localized attenuation A , in a manner known per se.

30 A tube which has the above characteristics and which corresponds to this first portion of the tube of Fig. 1 already enables a higher gain to be obtained than it is possible to obtain in tubes provided with a localized attenuation according to the known construction. A subsequent improvement can however be obtained by applying other arrangements according to the invention, which 35 are shown in Fig. 1.

The radio-frequency energy of the first travelling-wave tube $K_1 H_1 C_1$ controls the electrons of a second beam F_2 which is emitted by a cathode K_2 located outside the helix H_1 at an intermediate point of same. This beam propagates outside the helix H_1 and interacts with a second helix H_2 which is located outside the beam F_2 , for example in the axis of the helix H_1 , and which is of the same diameter as said helix H_1 . In this manner, the electrons of the second beam F_2 are velocity-modulated along the last portion of the helix H_1 , after which the modulated beam produces in the helix H_2 a radio-frequency wave that propagates towards the output. The electrons of the beam F_2 are collected by a collector C_2 , while the radio-frequency energy is collected at the output in the known manner, for example by coupling the output to a guide not shown. The helix H_2 is provided at its input end with a layer R_2 of resistance material arranged on the quartz rods T_2 or on the wire, said layer producing sufficient attenuation for the radio-frequency energy which is being propagated from the output towards the input end to be completely absorbed at the input end of the helix H_2 .

The cathode K_2 , which is shown in section in Fig. 1, may be of annular shape which is only broken if necessary by the rod or rods T_1 . In this case, the beam F_2 substantially completely surrounds the helix H_2 and consequently, for a given cathode current, has a smaller space charge than in the case in which the beam is located inside the helix. Thus, the unfavorable effect of the space charge on the gain remains slight.

The focusing of the two beams in the direction of the helices is obtained by means of a magnetic field along the axis of the tube, in the manner which is known in the tubes of usual construction.

With a tube according to Fig. 1, there is not only the advantage of being able to obtain a higher gain than in the known designs, but there is furthermore the possibility of obtaining the necessary absolute radio-frequency power which is required at the output of a station, such power being determined by the current of the cathode K_2 and by the accelerating voltage of the beam F_2 .

Fig. 2 shows a modified embodiment of the principles of the invention. The elements which are similar to those of Fig. 1 have been designated by the same reference letters. The difference with respect to Fig. 1 is that the helices are housed in a metal casing M which, together with the helix H_2 , determines a radial field which is used to control the beam F_2 . The cathode K_2 is again annular but the helix H_2 is no longer located inside but outside the beam F_2 . The collectors C_1 and C_2 can thus be combined into one member, thereby facilitating the supplying and cooling of the collector C_1 .

My invention is not restricted to the examples which have been described and illustrated, but on the contrary can be subjected to any modifications that an expert might be able to make therein without altering its principle.

What I claim is:

1. A travelling-wave tube comprising inside a single casing a chain of systems, each of which comprises a source of an electron beam, a collector positioned at the extremity of the path of the beam for collecting the electrons of the beam, and a retardation line extending parallel to the path of said beam, the output of a retardation line of a first system, which has a beam passing inside

said line, being coupled to the beam of a second system, that passes outside said line, the beam of said second system being in turn coupled to the retardation line of said second system in a subsequent portion of the tube.

2. A travelling-wave tube comprising inside a single casing a chain of systems, each of which comprises a source of an electron beam, a collector positioned at the extremity of the path of the beam for collecting the electrons of the beam, and a retardation line extending parallel to the path of said beam, the output of a retardation line of a first system, which has a beam passing inside said line, being coupled to the beam of a second system, that passes outside said line, the beam of said second system being in turn coupled to the retardation line of said second system in a subsequent portion of the tube, said second beam being located outside the said corresponding retardation line.

3. A travelling-wave tube comprising inside a single casing a chain of systems, each of which comprises a source of an electron beam, a collector positioned at the extremity of the path of the beam for collecting the electrons of the beam, and a retardation line extending parallel to the path of said beam, the output of a retardation line of a first system, which has a beam passing inside said line, being coupled to the beam of a second system, that passes outside said line, the beam of said second system being in turn coupled to the retardation line of said second system in a subsequent portion of the tube, this second retardation line being located outside the said corresponding beam.

4. A travelling-wave tube comprising inside a single casing a chain of systems, each of which comprises a source of an electron beam, a collector positioned at the extremity of the path of the beam for collecting the electrons of the beam, and a retardation line extending parallel to the path of said beam, the output of a retardation line of a first system, which has a beam passing inside said line, being coupled to the tubular-shaped beam of a second system, that passes outside said line, said tubular-shaped beam being in turn coupled to the retardation line of said second system in a subsequent portion of the tube.

5. Travelling-wave tubes comprising inside a single casing a chain of systems, each of which comprises a source of an electron beam, a collector positioned at the extremity of the path of the beam for collecting the electrons of the beam, and a retardation line extending parallel to the path of said beam, the output of a retardation line of a first system, which has a beam passing inside said line; being coupled to the beam of a second system, that passes outside said line, the beam of said second system being in turn coupled to the retardation line of said second system in a subsequent portion of the tube, said second retardation line being located outside the said corresponding beam, and the collectors of the successive systems being combined in a single member.

6. Travelling-wave tubes comprising inside a single metal casing a chain of systems, each of which comprises means for producing and accelerating an electron beam, a collector positioned at the extremity of the path of the beam for collecting the electrons of the beam, and a retardation line extending parallel to the path of said beam, the output of a retardation line of a first system, which has a beam passing inside said line, being coupled to the beam of a second system, that passes outside said line, the beam of said

second system being in turn coupled to the retardation line of said second system in a subsequent portion of the tube, the retardation line of said second system being located outside the said corresponding beam.
